UNITED STATES PATENT OFFICE.

HIRAM H. PEIRCE, OF PEORIA, ILLINOIS.

DESIGN FOR A CAMPAIGN-BADGE.

SPECIFICATION forming part of Design No. 33,184, dated September 11, 1900.

Application filed July 6, 1900. Serial No. 22,754. Term of patent 3½ years.

To all whom it may concern:

Be it known that I, HIRAM H. PEIRCE, a citizen of the United States, residing at Peoria, in the county of Peoria and State of Illinois, have invented and produced a new and original Design for a Campaign-Badge, of which the following is a specification, reference being had to the accompanying drawings, forming part thereof.

10 Figure 1 shows a general outline view of my badge, and Fig. 2 is a vertical section through the same.

15 As shown in the drawings, the leading or material feature of my design consists in the representation of a hat comprising a sugar-loaf crown A, having the indentation or crease a, the brim B having a rolling formation and caught up and fastened to one side of the crown of the hat, as at b. Projecting from the rear of the badge is shown a pin C.

20

Having described my invention, what I claim as new, and desire to secure by Letters Patent, is—25 The design for a campaign-badge, as herein shown and described.

In testimony whereof I have signed my name to this specification in the presence of two subscribing witnesses.

HIRAM H. PEIRCE.
